UNITED STATES PATENT OFFICE.

DAVID P. CUMMINGS, OF NEWTON, MASSACHUSETTS, ASSIGNOR TO TURF TREAD CORPORATION, OF BOSTON, MASSACHUSETTS, A CORPORATION OF MASSACHUSETTS.

INSOLE FOR SHOES.

Application filed January 15, 1925. Serial No. 2,645.

This invention relates to insoles for boots and shoes and is intended to provide an improved tread surface for the foot, of a character tending to control undue slipping of the foot on the shoe bottom, while also affording certain hygienic advantages incident to the use of such a tread surface.

To this end the invention is characterized by an insole provided with a tread surface having a close or thick pile projecting upwardly to engage the bottom of the inserted foot, the pile threads being of relatively stiff material such as wool or hair usually slightly inclined to the plane of the fabric for purposes hereinafter described.

As such a fabric should have means for keeping it from displacement or wrinkling, I provide a stiffening layer of suitable material such as thin sole-leather, stiffened canvas or both combined to act as a stiffening or retaining member to keep the more flexible pile fabric smooth and even.

In the accompanying drawings I have illustrated several forms of utilizing the principles of this invention to meet different conditions and special requirements, of which:

Figure 1 is a plan view of a shoe insole with a pile fabric insert cemented to a bottom holding layer of canvas which is cemented to the bottom of a cut out layer of sole-leather, the pile threads projecting above the level of the sole leather layer to support the bearing parts of the tripod of the foot.

Figure 2 is a side elevation thereof partly in section.

Figure 3 is a central longitudinal section through the fore-part of a welt shoe having an insole construction like that shown in Figures 1 and 2.

Figure 4 is a central vertical section through the longitudinal axis of a shoe containing a pile fabric insole of sole leather covered throughout with pile fabric and omitting the bottom reinforcing layer of canvas.

Figure 5 is a plan view of the insole shown in Figure 4.

Figure 6 is a vertical section on the longitudinal axis of a shoe of the usual welt construction having a slip-in insole comprising a bottom layer of stiffening material and a top layer of pile fabric.

Figure 7 shows a vertical longitudinal section of an ordinary welt shoe having a special slip-in insole containing a yielding pad to support the forward or transverse arch of the foot for corrective purposes.

Figure 8 is an enlarged view of the arch-supporting insole shown in Figure 7 detached from the shoe.

Figure 9 is a plan view of the insole shown in Figures 7 and 8.

The underlying principle of this invention is the utilization of a fabric having a relatively stiff and close pile as a foot-supporting and engaging element, such for example as is afforded by the cut pile of a closely woven velvet carpet or by mohair plush.

Since such pile fabrics are in themselves comparatively flexible, I provide one or more additional layers of stiffening material to retain the pile fabric in place and prevent it from wrinkling. Usually the cut pile threads are inclined somewhat to the plane of the body or web of the fabric and this results in producing a tendency of the foot to shift very slightly in the direction of such inclination, so that if a person troubled with pressure of the shoe upper against, let us say, the outside of the foot or on the little toe, a disposal of the pile fabric layer with its pile inclined toward the inside of the shoe will be found to afford relief from such pressure. Usually however when using a fabric with an inclined cut pile, I prefer an arrangement with the pile threads inclined rearwardly or toward the heel, because the tendency is to keep the heel of the foot snugly against the back or counter of the shoe and prevents the foot from thrusting forwardly into the narrow or toe portion of the fore-part while relieving pressure against the instep when walking.

In the practice of the invention according to the form illustrated in Figures 1-3, I use for the shoe insole a layer of thin sole leather 1, to the bottom of which is cemented a reinforcing layer of canvas 2. At the bearing points of the foot, namely, the ball and the heel suitable apertures or openings are cut out to form retaining pockets as indicated at 1^a and 1^b for receiving and retaining ball and heel inserted layers 3 and 4 of

2
cut-pile fabric whose pile is close and firm. The pile fabric layers are cemented to the reinforcing bottom layer 2, and may if desired be further secured by stitching as indicated at 3^a and 4^a though usually the stitching will not be needed. In this form the cut-pile threads should project upward somewhat beyond the level of the upper surface of the sole leather layer in order that it may have supporting contact with the superimposed foot. As indicated in Figures 2 and 3, the cut-pile threads are inclined rearwardly to oppose the tendency of the foot to thrust forward in the shoe when walking.

In Figures 4 and 5 the insole 5 is the usual sole leather insole without the cut-out pockets above mentioned and in this case the pile fabric layer 6 is cemented directly to the top surface of the sole leather or stiffening layer, and covers the whole surface. While I have mentioned sole leather as the material for the stiffening layer or element 5 it will be understood that any suitable or known substitute for sole leather insoles may in like manner be used for this purpose.

In Figure 6 is shown a slip-in insole comprising a stiffening layer 7 and a pile fabric layer secured to the top surface of the stiffening element. This insole is intended to make the invention applicable to shoes already made or being worn. As it is desirable that the over all thickness of such insole be as thin as possible consistent with its proper functioning in the shoe, the bottom or stiffening layer 6 is preferably made of thin laminated canvas or duck glued or cemented together and a layer of adhesively coated mohair plush cemented thereto.

40 In Figures 8 and 9 I have shown a special form of arch-supporting insole, provided with an elastic compressible pad inserted in a pocket or space between the stiffening element or layer 9 and the pile fabric element or layer 10. As will be noticed, this type of insole is short extending only from the heel to the ball portion of the shoe. In practice, the pile fabric layer 10 may be cemented to the stiffening layer 9 over the whole top surface thereof and the small disk 11 of sponge rubber or like compressible material may be inserted after the two layers have been separated by a thin blade to form a space or pocket at the front end of the short insole in position to raise and yieldingly support the pronated or fallen transverse arch of the foot, the outline of such interspace or pocket being indicated by dotted line 11 of Fig. 9. Such arrangement permits the adjustment of the arch supporting pad to precisely the correct position to raise the meta-tarsal bones of the foot and also allows replacement of a compacted pad by a new one.

60 To prevent such shifting or displacement of the short insole as would lead to an in-

correct positioning of the pad 10, I provide adhesively coated flexible tongues or tabs 12 which may be turned under the outer edge of the insole at the heel as shown in Figure 7 or may be adhesively attached to the lining of the heel counter.

Since the upper layer over the pad is of yielding material whose action is beneficial and agreeable to the foot, the formation of a small mound or protuberance beneath this portion of the foot has no tendency to produce callous spots on the bottom of the foot.

In practice I have found that the use of a cut-pile fabric insole element exposed to contact with the foot in the various ways above indicated not only renders shoes more comfortable and agreeable to the wearer than when the foot rests directly upon hard sole leather, but that such contact has a marked hygienic value by promoting blood circulation in the foot and invigorating the muscles thereof by the constant but gentle massage obtained from the pile fabric when walking or moving about. This is markedly noticeable in cold weather in the case of those troubled with coldness of the feet due to sluggish circulation, and makes it possible for those who are so troubled to wear low-cut shoes, with comfort, in the winter as well as in the summer.

Ordinary stockings do not interfere with the described action of the cut pile threads on the bottom of the foot. Where the short insole is used any suitable means may be employed for anchoring it against displacement in the shoe, but as it may be necessary to pull back the forepart of such insole to gain access to the pad-containing pocket for the purpose of replacing the pad, the adhesive attaching tabs are preferred to coating the bottom of the insole with cement and thus gumming or cementing it to the inside face of the shoe bottom, particularly as the usual leather insole, after a substantial period of contact with the foot, absorbs so much moisture that it does not form a good surface for the adhesion of a cementing or gumming medium.

In cases where there is not a pronounced inclination of the cut pile of the mohair plush, such an insole will, in some instances, maintain its position when it is shaped to the contour of the shoe bottom by the pressure of the foot, particularly if the outline of the insole is cut large enough to snugly engage the surrounding upper where it joins the insole.

The alternate collapsing and straightening of the pile threads have a substantial ventilating effect and thus, coupled with the more or less non-absorbent nature of the fibre forming the pile, serves to minimize the absorption of moisture from the foot.

When the composite insole is built in to the shoe after the fashion illustrated in

Figures 4 and 5, for example, the heel portion of the mohair plush or pile fabric is stripped from the base layer and is turned down over the arch portion with the gummed side uppermost and the shoe is lasted with this layer folded in the manner described in order to avoid driving the heel-attaching nails through the pile fabric layer. After the shoe is removed from the last the folded over portion can be restored to its normal position and cemented to the underlying heel portion of the base layer, thus covering up the heel attaching nails and at the same time protecting the heel from contact therewith.

What I claim is:—

1. A shoe bottom provided on its interior with a layer of textile fabric formed with closely arranged pile threads whose cut ends, projecting upwardly from the shoe bottom, form a multiplicity of foot-contacting spines to yieldingly support a superimposed foot, substantially as described.
2. A shoe bottom whose inner side is provided with a layer of textile fabric formed with a multiplicity of closely arranged pile threads whose cut ends project upwardly with a rearward inclination to form a multiplicity of foot-contacting spines which yield rearwardly under the pressure of the foot, substantially as described.
3. A shoe bottom embracing in its construction a relatively stiff body element and a relatively flexible element of textile fibre having upwardly projecting, closely ar-
4. ranged thread ends forming an elastic pile in supporting contact with the sole of a superimposed foot, said textile fibre element being secured to the shoe-bottom by a cementing adhesive applied to its under side, substantially as described.
5. In a shoe, the combination of an outer sole and a laminated inner sole having a foot-engaging layer of pile fabric with the cut ends of the pile threads projecting upwardly to engage and support the foot, substantially as described.
6. A tread layer for the interior of a shoe bottom comprising a textile fabric element having short, thick cut-pile threads projecting upward to form an elastic foot-contacting tread, substantially as described.
7. An insole for a shoe embracing a layer of mohair plush corresponding substantially to the contour of the shoe insole and provided on its bottom with a coating of adhesive for cementing it, pile threads uppermost, to the inside face of the shoe bottom.
8. A shoe insole embracing a relatively stiff foundation layer and a top layer of mohair plush secured to said foundation layer to prevent displacement, the closely arranged upwardly projecting short pile thread ends of the plush being inclined toward the heel end of the insole to yield rearwardly under the pressure of the wearer's foot.

In witness whereof, I have subscribed the above specification.

DAVID P. CUMMINGS.
